UNITED STATES PATENT OFFICE.

FRANK S. HAEFNER AND LEWIS F. ZWEIBEL, OF WILKES-BARRE, PENNSYLVANIA.

SAND SEPARATING AND BLENDING MACHINE.

Application filed May 24, 1928. Serial No. 280,254.

This invention relates to sand separating and blending machines used in metal foundries to break up lumps of used sand and mix it with new sand, and separate all pieces of 5 iron, pebbles and other unsuitable material from the mixed sand, and aerate and blend the same so that it is put into good condition for use in making the molds in which metal is cast. This invention consists of a 10 centrifugal machine having a rotary wheel provided with toothed combs at its periphery combined with other necessary parts and screens as hereinafter fully described and claimed.

15 In the drawings, Fig. 1 is a side view of a sand separator and blander constructed according to this invention, with two ground wheels left out, and portions of the casing broken away to show some of the parts inside it. Fig. 2 is a cross-section through the machine, taken on the line 2—2 in Fig. 1. Fig. 3 is an end view of the machine, looking from the rear. Fig. 4 is a side view of a portion of the wheel showing two toothed 20 combs, and is drawn to a larger scale. Fig. 5 is a plan view of the parts shown in Fig. 4. Fig. 6 is a cross-section, taken on the line 6—6 in Fig. 4, and also showing the retaining ring for the toothed combs.

25 The machine is provided with a casing 8 which is preferably mounted on ground wheels 9 for convenience of transportation, and is provided with a hinged draft tongue 10 at its front end.

30 A rotary wheel 12 is secured on a shaft 14 and is arranged inside the casing. The shaft is journaled in bearings 15 on the casing, ball bearings or other anti-friction bearings being preferably used, and a driving pulley 16 is secured on the shaft outside the casing. The wheel is preferably driven by an electric motor 17 of approved construction 35 enclosed in a compartment 18 at the upper part of the casing, and connected to the pulley by a belt 19. The wheel may however be driven by any other approved means. The wheel is formed of two disks or plates 20 spaced apart and provided with notches 21 at their peripheries.

40 These notches are wedge-shaped, and are largest at their outer ends. Toothed combs 24 are provided, and have pivots 25 at their ends, which are mounted to rock in the notches 21. Each comb consists of a flat 45 blade having teeth 26 arranged at an angle to the blade, and projecting forwardly of it

when the blade is at the top of the wheel. The teeth of the blades are staggered, as shown in Fig. 5, the blades being arranged alternately in two series. The shape of the 50 notches permits the blades to have a rocking motion, and the extent of the rocking motion is limited by the flat sides of the pivots which come in contact with the sides of the notches, as indicated by dotted lines in Fig. 4. 55 The wheel is driven at high speed in the direction of the arrow in Fig. 1, and its toothed combs are controlled by centrifugal force. The toothed combs are retained in the notches of the wheel by flanged retaining 60 rings 27, formed in sections and secured to the sides of the disks. The flanges overlap the pivots of the combs, and the sections of the rings permit as many as desired of the 65 combs to be removed.

70 A feed hopper 28 for the sand is provided at the front part of the casing above the front half of the wheel, and an inclined screen 29 is secured in the upper part of this hopper. Curved guard plates 30 and 31 are secured 75 in the casing under the lower and front parts of the wheel, and an opening 32 is arranged between the guard plates under the center of the wheel for the discharge of anything which may fall upon the guard plates, 80 and for the inlet of air from the bottom of the casing which is left open, and is supported above the level of the ground.

85 A trap door 34 is pivoted to the casing by a pin 35, and normally closes the space 90 or passage 33 between the casing at the bottom front edge of the hopper and the top edge of the front guard plate 31. The trap door is provided with a handle 36 for opening it.

95 The weight of the handle may be arranged to permit the trap door to open automatically when material accumulates upon it. The trap door normally rests against a lug 37 on the guard plate.

100 Doors 40 are secured over openings 41 in the sides of the casing, so that when a few combs require to be removed, the sections of the rings 27 which hold them in place can be removed without disturbing the rest of the combs.

105 The rear side of the casing is provided with a screen 42 mounted in a frame 43 which is slidable vertically in guides 44 on the casing. This screen can be removed and replaced as often as desired, and screens of various mesh 110 can be used, or the screen can be omitted altogether.

A flexible toothed comb 45 is secured to the rear side of the hopper over the center of the wheel. This comb 45 has teeth of resilient material, and it is provided to retain the material temporarily in the hopper, and to permit any hard objects which may be caught in the combs of the wheel to pass to the rear without damaging the machine.

The sand is fed or thrown onto the receiving screen, and falls through it onto or against the rapidly moving toothed combs of the wheel, and these combs carry it under the flexible comb 45, and blend and mix it, and discharge it by centrifugal force through the screen 42 onto the ground, or into any suitable receptacle placed to receive it. The screen 29 in the hopper prevents large lumps from being thrown onto the wheel, and lets the sand fall gently onto the wheel.

20. What we claim is:

1. In a sand separator and blender, a casing having an inlet opening for sand at its upper front part, a rotary wheel mounted in the casing and provided with toothed combs at its periphery, curved guard plates secured in the casing under the wheel leaving an opening under its axis, and a detaining device for the sand secured over the top of the wheel to the rear of the said inlet opening.

2. In a sand separator and blender, a casing having an inlet opening for sand at its upper front part, a rotary wheel mounted in the casing and provided with toothed combs at its periphery, a curved guard plate secured under the front and lower part of the wheel and forming a passage with the casing, and a trap door normally closing the said passage.

3. A sand separator and blender as set forth in claim 2, the said trap door being pivoted to the casing and arranged to open downwardly.

4. A sand separator and blender as set forth in claim 2, the said trap door being pivoted and arranged to open automatically when solid matter accumulates upon it.

5. In a sand separator and blender, a casing having inlet and outlet openings for sand and having also an opening in its side, a removable cover for the side opening, and a rotary wheel mounted in the casing and provided with removable toothed combs at its periphery, the said side opening being provided for the removal of the toothed combs.

6. In a sand separator and blender, a casing having inlet and outlet openings for sand, a rotary wheel mounted in the casing and provided with tilting toothed combs at its periphery, and a detaining device for the sand secured above the wheel to the rear of the sand inlet opening.

7. A sand separator and blender as set forth in claim 6, the said toothed combs being formed of flat blades and teeth arranged at an angle to the blades.

8. A sand separator and blender as set forth in claim 6, the said toothed combs being arranged in two alternating series with the teeth of one series arranged in staggered relation to the teeth of the other series.

9. A sand separator and blender as set forth in claim 6, the said wheel having disks provided with wedge-shaped notches in their peripheries, and the said blades being pivoted to rock in the said notches to a predetermined extent.

10. A sand separator and blender as set forth in claim 6, the said wheel having disks provided with notches in their peripheries, and the said blades being provided with pivots which engage with the said notches, and retaining devices secured to the said disks and keeping the blades in place.

11. A sand separator and blender as set forth in claim 6, the said wheel having disks provided with notches in their peripheries, and the said blades being provided with pivots which engage with the said notches, and rings formed in sections secured to the said disks and provided with retaining flanges which overlap the notches and the pivots in them.

12. In a sand separator and blender, a casing, a rotary wheel mounted in the casing and provided with tilting sand impelling devices at its periphery which are projected radially when the wheel is rotated rapidly, and a detaining device for the sand secured in the upper part of the casing out of contact with the sand impelling devices and arranged crosswise of the path of the sand driven off by the sand impelling devices.

13. A sand separator and blender as set forth in claim 12, the said detaining device comprising a toothed comb arranged substantially radial of the axis of the said wheel.

14. A sand separator and blender as set forth in claim 12, the said wheel being provided with means for limiting the deflection of the sand impelling devices when they strike hard lumps in the sand.

15. In a sand separator and blender, a casing having a substantially vertical sand delivery screen and an opening at its bottom adjacent to the said screen, a rotary wheel mounted in the casing and provided with sand impelling devices at its periphery, and a detaining device for the sand secured in the casing adjacent to the sand impelling devices.

16. A sand separator and blender as set forth in claim 15, the said casing being provided with guides, and the said screen being removable and slidable in the said guides.

In testimony whereof we affix our signatures.

FRANK S. HAEFNER.
LEWIS F. ZWEIBEL.
